Inventor:-

UNITED STATES PATENT OFFICE.

JUSTUS VERSCHUUR, OF JERSEY CITY, NEW JERSEY.

DESIGN FOR A SPOON.

SPECIFICATION forming part of Design No. 22,679, dated August 8, 1893.

Application filed May 2, 1893. Serial No. 472,794. Term of patent 3½ years.

To all whom it may concern:

Be it known that I, JUSTUS VERSCHUUR, a citizen of the United States, residing at Jersey City, in the county of Hudson and State 5 of New Jersey, have invented and produced a new and original Design for a Spoon; and I do hereby declare the following to be a full, clear, and exact description of the invention, such as will enable others skilled in the art to 10 to which it appertains to make and use the same, reference being had to the accompanying drawings, and to letters of reference marked thereon, which form a part of this specification.

15 In said drawings Figure 1 is a plan of the front or obverse side of the spoon and Fig. 2 is a plan of the reverse side, these views being deemed sufficient to illustrate the design.

The leading features of the design consist 20 in the ornamentation of the obverse side of the spoon, that of the reverse and in the general shape and ornamentation of the spoon as a whole.

Of the spoon, *a* indicates the bowl, *b* the 25 shank and *c*, the flange or wider part of the handle. On the obverse side, the bowl is decorated with a perspective view of the Children's Home Building, *d*, of the World's Columbian Exposition. The wider portion of the flange 30 presents the portrait, *e*, of a lady more or less closely resembling Mrs. Potter Palmer, the

outlines of the face and bust being displayed within and independent of the outlines of the flange below which portrait, the flange is ornamented with a spray of flower-like decorations *f*. Toward the shank, *b*, the flange is in turn, decorated with a representation of a hemisphere, *g*, on which an eagle, *h*, is represented as standing with outstretched wings. On the reverse side, the wide part of the flange 35 presents the figure of a child, *i*, walking under a large parasol or umbrella as though in the act of playing "Going to the World's Fair." Below this decoration are chaplets or sprays 40 of laurel, a coat of arms or shield *k*, of the United States, showing the stars and stripes as usually arranged, and below this a hemisphere *l*.

What I claim as new is—

1. The design for the obverse of a spoon as 50 shown and described.
2. The design for the reverse of a spoon as shown and described.
3. The design for a souvenir spoon as shown and described.

In testimony that I claim the foregoing I have hereunto set my hand this 10th day of April, 1893.

JUSTUS VERSCHUUR.
